(No Model.)

J. M. & W. H. CURTICE.
Churn.

No. 240,508.

Patented April 26, 1881.

UNITED STATES PATENT OFFICE.

JESSE M. CURTICE AND WILLIAM H. CURTICE, OF MOUNT STERLING, KY.

CHURN.

SPECIFICATION forming part of Letters Patent No. 240,508, dated April 26, 1881.

Application filed April 7, 1880. (No model.)

To all whom it may concern:

Be it known that we, JESSE M. CURTICE and WM. H. CURTICE, of Mount Sterling, in the county of Montgomery and State of Kentucky, have invented certain new and useful Improvements in Churns; and we do hereby declare the following to be a full, clear, and exact description of the invention, such as will enable others skilled in the art to which it pertains to make and use it, reference being had to the accompanying drawings, which form part of this specification.

Our invention relates to an improvement in churns, the object being to provide a simple and efficient device for operating a churn-dasher; and the invention consists in certain details of construction and combinations of parts, as will hereinafter be described, and pointed out in the claims.

In the accompanying drawings, Figure 1 is a view in perspective of our improvement. Fig. 2 is a view in side elevation, showing the churn-dasher raised for the insertion of the body of the churn. Fig. 3 is a plan view of the improvement. Fig. 4 is a detached view of the actuating-lever. Fig. 5 is a detached view, showing renewable bearings for the shaft.

A represents the base, to which is secured the standard B, having two arms, C D, cast solid therewith. Standard B and arms C D are preferably cast hollow, thereby insuring cheapness and lightness in manufacture, and may be formed of any suitable design and ornamented to suit the taste of the maker.

The lower end of standard B may be provided with a perforated flange, through which screws are inserted to secure it to the base, or it may be screwed into the base or secured thereto in any manner desired.

E is the dasher-shaft, formed with a sleeve or pulley, F, near its upper end.

Above and below the part F of dasher-shaft E are the journals a a', which fit into the open or half bearings G G', formed in the outer ends of the arms C D. Bearings G G' may be formed in the arms, or renewable bearings of Babbitt or other metal may be removably secured within the outer ends of said arms. The elongated pulley F of the dasher-shaft fits between the arms, thus supporting the dasher-shaft and

preventing any end movement of the same while in operation.

H is the actuating-lever. It is provided with a perforated bearing-plate, h, at its center, which fits into a horizontal slot, h', in the upper end of the standard, and is therein retained by a pivot, I, inserted in the top of the standard and passed downwardly through the hole i in the horizontal bearing-plate.

Upon the opposite ends of the actuating-lever are pivoted the knobs or handles K K', of such form and size as to be easily grasped by the operator. Actuating-lever H is also furnished with the arms L L', to the outer ends of which are secured the pins M M', each having a rounded button-head, m.

N N' are straps, each being secured at one end to the sleeve or elongated pulley F on the dasher-shaft, while their opposite ends are provided with holes n, one or more, to allow the straps to be removably secured to the pins M M' on the arms of the actuating-lever.

Straps N N' may be made of leather, woven fabric, rawhide, or very thin and flexible metal, as thin sheet-brass; or, in lieu of straps, we may use cords or wire, and instead of forming holes in the ends of the straps for attaching them to the arms of the actuating-lever, rings or hooks may be secured to the ends of the straps for such purpose. To compensate for the stretching of the straps, a chain, of two or more links, may be attached to the ends of the straps, and the links of the chain connected with the pins on the arms of the actuating-lever.

O is the main dasher, it being formed as a continuation of the dasher-shaft, or it may be separately formed and secured to the dasher-shaft. Dasher O is broad and flat, with square edges o.

To the main dasher O are secured the oval-shaped dasher-blades P P', their upper ends being of greater width than their lower ends.

The operation of the device is as follows: Milk is poured into the churn-body, and the latter inserted in place by unhooking or unbuttoning one of the straps, thereby releasing it from the actuating-arm, and raising the dasher, as illustrated in Fig. 2, then inserting the dasher in the churn-body, and moving the latter in vertical line beneath the dasher-shaft.

The strap is then connected with the arm of the actuating-lever, when all is in readiness for operating the churn. By imparting an oscillating movement to the actuating-lever the dasher-shaft is rapidly rotated in opposite directions, which has the effect of causing the milk to flow around the churn in one direction and then to be suddenly arrested and moved in the opposite direction. The churn-dasher thus strikes the globules of milk with sufficient force to most effectually break them and liberate the cream therefrom.

The curved dasher-blades are graduated in width from their upper to their lower ends, in order to relieve the churn of any undue load in operation.

The blades are the narrowest at the bottom, as they are there subjected to the greatest resistance, owing to the pressure exerted thereon by the column of milk in the body of the churn, while the upper ends of the curved dasher-blades are made widest, as the upper ends are not subjected to the weight of the milk in the body of the churn.

R is a quill or brush attached to the dasher-shaft to frighten away flies as the churn is being operated.

S is a fan, the handle s of which is inserted in a diagonal hole, s', in the upper end of the dasher-shaft, the fan serving to fan the operator while at work and render the operation of churning both a pleasant and agreeable pastime.

It is evident that many slight changes in de-

tails of construction and relative arrangement of parts might be resorted to without departing from the spirit of our invention, and hence we would have it understood that we do not limit ourselves to the exact construction and arrangement of parts shown and described; but,

Having fully described our invention, what we claim as new, and desire to secure by Letters Patent, is—

1. The combination, with a standard provided with arms having half-bearings in their outer ends, of a dasher-shaft, a horizontal actuating-lever provided with arms L L', and two cords or straps connected at one end with the dasher-shaft and at their opposite ends with said arms, substantially as described.

2. The combination, with the standard having a horizontal slot formed in its upper end, of an actuating-lever provided at its center with a perforated plate, which fits within the slot in the standard, and a pin or bolt extending from the top of the standard downwardly through the perforated plate, substantially as set forth.

In testimony that we claim the foregoing we have hereunto set our hands this 19th day of March, 1880.

JESSE M. CURTICE.
WM. H. CURTICE.
